UNITED STATES PATENT OFFICE

ANDREW VANDER LEY, OF GRAND RAPIDS, MICHIGAN, ASSIGNOR TO VANDER LEY BROS., INC., OF GRAND RAPIDS, MICHIGAN, A CORPORATION OF MICHIGAN

DESIGN FOR A CHAIR

Application filed December 12, 1931. Serial No. 42,048. Term of patent 14 years.

To all whom it may concern:

Be it known that I, ANDREW VANDER LEY, a citizen of the United States, residing at No. 716 Olympia St. S. W., Grand Rapids, in the county of Kent and State of Michigan, have invented a new, original, and ornamental Design for a Chair, of which the following is a specification, reference being had to the accompanying drawing, forming a part thereof, in which the figure is a perspective view of the chair, showing my new design.

I claim:

The ornamental design for a chair, substantially as shown.

ANDREW VANDER LEY.
